UNITED STATES PATENT OFFICE.

EDWARD STANLEY, OF NEW YORK, N. Y., ASSIGNOR TO THE NATIONAL PAPER BAG COMPANY, OF SAME PLACE.

MACHINE FOR MAKING PAPER BAGS.

SPECIFICATION forming part of Letters Patent No. 253,441, dated February 7, 1882.

Application filed October 21, 1881. (No model.)

To all whom it may concern:

Be it known that I, EDWARD STANLEY, of the city of New York, in the county and State of New York, have invented certain new and 5 useful Improvements in Machines for Making Paper Bags, of which the following is a specification:

My invention relates to machines for making paper bags from a continuous web of paper. In such machines the paper is drawn forward from a feed-roller in a continuous web, and is first passed between feed-rollers, which move it forward continuously; thence between two rollers, one of which carries in it a reciprocating knife for cutting the paper off into 15 blanks of proper length to form bags; thence between folders, which turn over or fold the sides of the blank so that they will lap over each other to form the longitudinal seam; thence between a paste-box and adjacent roller, by which paste is applied to the end and the flap at the bottom of the bag; and thence between other rollers, which turn over and press down the flap to close the bottoms of the bags, 25 and which deliver the bags from the machine.

The present invention consists in certain improvements in the construction of the knife which cuts the belt or web of paper to form the blanks; also, in an improved construction 30 of the roller in which said knife is carried, and of the roller which operates in combination therewith; also, in an improved combination of mechanism for reciprocating the paste-box, so that it will move at the same speed as the 35 bags to which the paste is being applied; also, in an improved arrangement of a supporting-plate, which holds the bags against the paste-roller carried by the paste-box; and, further, in an improved combination of mechanism for 40 raising and lowering the aforesaid paste-plate, and an elastic creasing-roller, against which a creasing knife or blade carried by the paste-box works, so that after paste has been applied to the bottom portion of the bags and 45 the bottom flaps have been creased the remaining or upper portion of the bags will move freely between the paste-roller and supporting-plate without being pasted or acted upon by the creasing knife or blade.

50 In the accompanying drawings, Figure 1

represents a longitudinal vertical section of my improved machine. Fig. 2 represents a side view of the roller which rotates in contact with the roller which carries the reciprocating knife for cutting the belt or web of paper into 55 blanks. Fig. 3 represents a partial longitudinal section of said roller and its adjacent roller, between which the belt or web of paper passes. Fig. 4 represents an end view of said rollers and devices for moving the knife. Fig. 5 represents a plan of the complete knife. Fig. 6 represents a similar view of a portion thereof on a larger scale. Fig. 7 represents a side view of a portion of the knife on the same scale as Fig. 6. Fig. 8 represents a plan of a portion 65 of the knife on the same scale as Figs. 6 and 7. Fig. 9 represents a transverse section of the knife on the dotted line $x\ x$, Fig. 7. Fig. 10 represents a similar section of the knife on the dotted line $y\ y$, Fig. 7. Fig. 11 represents a 70 plan of a portion of the paper belt or web, showing the lines on which it is cut. Fig. 12 represents a plan of one of the blanks. Fig. 13 represents a plan of a bag before the bottom flap is closed over the bottom. Fig. 14 75 represents a longitudinal vertical section of the delivery-end portion of the machine, including the paste-box and all its appurtenances, and upon a larger scale than Fig. 1. Fig. 15 represents a transverse vertical section on the 80 dotted line $z\ z$, Fig. 14. Figs. 16 and 17 are detail views, hereinafter explained.

Similar letters of reference designate corresponding parts in all the figures.

A designates the frame of the machine, and 85 B designates a driving-shaft, to which motion may be communicated by a driving-belt passing over pulleys thereon.

C designates a roll of paper, and a designates the continuous belt or web of paper drawn 90 therefrom and passed around a roller, a' , and thence between a pair of feed-rollers, $b\ b'$, the first of which is rotated positively, and the second of which rotates by frictional contact with the web of paper.

Motion may be transmitted to the roller b in 95 any suitable manner—as, for example, by a shaft extending transversely to the driving-shaft B and the roller b . After the paper is fed forward by the feed-rollers $b\ b'$ it is carried 100

between two rollers or cylinders, D D', which rotate in contact with each other, and the latter of which carries a knife for dividing the web of paper transversely into blanks of proper length to form bags. The two rollers D D' are geared together by wheels c, as seen in Fig. 3, and upon the shaft of the lower roller, D, is a gear-wheel, c'. Motion is transmitted to the lower roller, D, by means of a gear-wheel, c², 5 on the main shaft B, and an intermediate wheel, c³, engaging with the wheels c' and c², as clearly seen in Fig. 1. In unwinding the paper from the roll C it is found that the paper tends to curve or curl upward after passing the rollers D D'. When the roll C of paper is large in diameter the deflecting of the paper over the roller a' is sufficient to take the curl out of the paper, but as the roll becomes smaller it is insufficient to straighten the paper. To take 10 this curve or curl out of the paper I form the lower roller, D, with projecting circumferential beads d, and the upper roller, D', with corresponding circumferential grooves, d', and as the paper is passed between the two rollers it 15 is slightly corrugated longitudinally near each edge by the beads d and grooves d', and such corrugation tends to straighten the paper and prevents the blanks, after being cut off by the knife carried by the roller D', from curling up. 20 These rollers, with their beads and corresponding grooves, I regard as of great importance, as they accomplish effectively the straightening of the paper, and they may be used in other machines for straightening a continuous belt 25 or web of paper. The portions of the rollers D D' on the outside of and between the beads d and grooves d' are cylindric and of uniform diameter.

I will now describe the construction of the 30 knife which is carried in the upper roller, D', and the means whereby it is operated. This knife is employed for cutting the belt or web of paper a transversely on the lines a², as seen in Fig. 11, and it will be observed that the 35 cuts a² are irregular, and the blanks a³, into which the paper is divided, have each a projecting flap, a⁴, which, when the blank is folded on the lines a⁵ (see Fig. 12) so as to unite the side edges, is folded over the open bottom and 40 pasted down to close the bottom.

It will be understood that the length of the flap a⁴ will vary in bags of different sizes, and hence a knife having a blade of different form must be used. The knife is represented in Figs. 55 5 to 10, inclusive.

The stock of the knife is composed of a straight piece or bar, e, and a curved piece or bar, e', attached thereto at both ends. The straight piece or bar e is cut away in the middle of its 60 length on the under side, and the piece e' is slit longitudinally at each end, as seen in Fig. 7, so as to form two fingers or projections, e² e³. The upper fingers, e², are firmly secured to the piece e by screws e⁴, or otherwise, as seen in 65 Figs. 6 and 7; but the lower fingers, e³, are bent farther inward, as seen in Figs. 6 and 8,

and project under the cut-away portion of the piece e at each end of the piece e'.

The blade of the knife is composed of three portions, f f' f''. The pieces or portions f are 70 soldered to the inner side of the stock-piece e at each end thereof, and the portion f' is soldered to the stock-piece e', and is adapted to fit between the pieces f. The manner in which the blade is fitted to the stock-pieces e e' is 75 shown in Figs. 9 and 10. It will now be understood that the bending of the lower fingers, e³, of the piece e' farther inward than the fingers e² brings the portions f' and f of the blade end to end and produces a continuous 80 cutting-edge, which may be toothed or serrated, as seen in Fig. 7, if desired, to increase its effectiveness.

In order to produce blanks having flaps a⁴ of different lengths, I provide a single stock-piece, e, with sections f f' of the blade permanently fixed thereto, and as many pieces e', with attached blade-sections f'', as I desire to make sizes of bags. The pieces e' are all of the same length from end to end; but their 85 straight portions at the ends are of different lengths, and consequently their middle portions, which are bowed outward from the piece e, will vary in length and are adapted to form flaps of different lengths. The piece e' shown 90 in Fig. 6 is bowed outward nearly to the ends, leaving only enough straight at the ends to fit on the piece e, and hence it is adapted for cutting a long flap. The piece e' shown in Fig. 6 is adapted for cutting the longest flap for 95 the widest bag which it is desired to make, and the piece e' shown in Fig. 8, and which is straight for a greater distance from the ends, is designed to cut a shorter flap for a narrower bag.

It will be seen that the removable stock-piece e' is of great advantage, as it enables me to readily adapt the knife for bags of various widths.

The knife is fitted in a longitudinal slot in 100 the upper roller, D', and is adapted to be reciprocated therein, so as to project beyond the periphery thereof. The lower roller, D, is provided with a slot to receive the edge of the knife shown in Fig. 2, and composed of narrow end portions, g g, and a wider intermediate portion g', which receives the blade portion f' of the knife, and which is as long as the piece e' shown in Fig. 6, and having the longest bowed or bent portion. Hence no modification 115 of the roller is necessary for knives of different sizes.

The knife-stock e is provided at each end with a block, f³, and is connected at the ends to two yokes, f⁴, by means of screws or studs 120 f⁵, which pass through the said yokes and enter the block f³. The yokes f⁴ are slotted, so as to receive the hubs on the ends of the roller D', and are secured on the ends of the roller D' by the gibbs f⁶, between which they slide, as seen 130 clearly in Fig. 4. When not otherwise actuated the yokes are moved to draw the knife

within the periphery of the roller by means of springs f^7 , which are secured in grooves in the periphery of the roller, as seen in Fig. 3; but springs might be otherwise arranged to produce the same result.

The yokes f^4 are provided with friction-rollers f^8 , and as the roller D' rotates, and when the knife is diametrically between the two rollers D and D' , the yokes are moved to cause the knife to protrude from its slot and cut the paper by means of stationary cams f^9 , attached to parts of the frame, and against which the rollers f^8 bear. By this means the knife is projected from the roller at the proper time, and is then withdrawn.

At the end of the machine at which the paper enters is a small elevated table, A' , upon which may be supported a paste-box for delivering paste upon one longitudinal edge of the strip or web of paper, so that when the two edges are folded so as to overlap they will be stuck together. As this pasting of the longitudinal edges forms no part of my invention, I have not here shown the appliances for doing it. After passing the rollers D - D' the blanks which have been cut off enter between a plate or platen, E , and an endless belt, F . (Shown clearly in Fig. 1.) The belt F is carried by rollers F' , to one of which motion may be communicated by gearing from the driving-shaft B , or in any other suitable manner. The upper or carrying part of the belt F passes over a series of rollers, h , which are mounted in stationary bearings, and by them the said upper part of the belt is pressed against the platen E , and as the friction between the belt and the paper blanks is greater than between said blanks and the platen or plate E the blanks will be carried forward by the belt.

I may here remark that the speed of the belt F should be slightly greater than the circumferential velocity of the rollers D - D' , so that the blanks will be moved forward a trifle faster than the web of paper from which they are cut.

On each side of the machine are folders G , which are spiral or twisted blades secured rigidly in place, but capable of adjustment toward and from each other. When the two opposite sides of the blanks meet these folders they are gradually turned up from a horizontal position to a vertical position, and then inward upon each other, thus folding the blank on the lines a^5 , Fig. 12.

Over the roller F' nearest the delivery end of the machine, and over which the belt F passes, is a small stationary roller, h' , under which the blanks pass, and which, in connection with the belt F , feeds them forward until they escape from under it.

I will now describe the mechanism for pasting the end of the bag and for creasing the blank preparatory to folding over the flap a^4 , (see Fig. 12,) and which is best shown in Figs. 14 and 15, but also in Fig. 1.

H designates the paste-box, which is mounted

in a movable carriage, H' , which is adapted to reciprocate along guides or slides H^2 .

I designates a shaft extending transversely across the machine and carrying a gear-wheel, I' , which engages with a wheel, I^2 , upon a shaft, I^3 . The shaft I^3 may have rotary motion imparted to it in any suitable manner—as, for example, by a shaft extending from and transversely to the main driving-shaft B and bevel-gearing.

Upon the shaft I are two cranks, i , and J designates connecting-rods, by which the crankpins of the cranks are connected with wristpins or studs i' , projecting from the sides of the carriage H' , as seen in Fig. 15.

In the open throat of the paste-box H is a paste-roller, j , and upon the end of the shaft of said roller is a ratchet-wheel, j' , (seen in Fig. 15,) which is adapted to strike against a stationary pawl or arm as the box reciprocates, whereby a fresh surface of the roller is brought into use.

Upon the paste-box H is a blade or scraper, k , which may be adjusted toward and from the roller j by means of set-screws k' , to cause its edge to press with more or less force upon the surface of the roller, and thereby regulate the quantity of paste carried out of the box by the roller.

Below the paste-box H is a shaft, K , mounted in stationary bearings, and upon this shaft is secured a roller, L , and immediately below the shaft K is another shaft, M , also mounted in stationary bearings. The shaft K derives motion from the shaft I^3 by means of a wheel, K' , engaging with the wheel I^2 . The shaft M derives motion from the shaft I^3 by means of a gear-wheel, M' , engaging with the wheel I^2 .

Upon the ends of the roller L are hubs l , and l' designates yokes which are slotted so as to fit over said hubs and slide thereon transversely to the shaft K and said roller L .

If desired, the yokes l' may be held upon the ends of the roller L by means of gibbs, which form guides or slideways, in which the yokes l' may move freely. The two yokes l' are connected at their ends by a supporting-plate, l^2 , for the bags, so that both yokes l' are caused to move simultaneously.

Upon the lower shaft, M , are two cams, N , placed opposite the yokes l' , and as said shaft is rotated these cams raise the yokes l' and the supporting-plate l^2 , so as to raise the latter into contact with the paste-roller j , or rather to cause it to press a bag up tightly against said roller. When the yokes l' are not acted upon by the cams N they are drawn down, or in the opposite direction, to move the supporting-plate l^2 nearer the shaft K , by means of a spring, l^3 , which extends from one yoke to the other, as seen in Fig. 15, and is secured in a groove, l^4 , in the roller L .

From the above it will be seen that the paste-box H is moved forward with its roller j immediately over the bottom portion of the bag, where it is desired to apply the paste, and

when the movement of said paste-box brings the roller *j* immediately over the plate *l*, the latter, having been raised gradually by the action of the cams *N* on the yokes, reaches its highest position and presses the bag against the roller *j* to deposit paste upon it. At this instant, however, the drop or let-off of the cams *N* passes the cam-shaped ends of the yokes *l*, and the yokes are drawn down by the springs *l*', lowering the plate *l* away from the roller *j*. When the plate *l* moves away from the paste-roller *j* the bag might stick to the roller, and to prevent this I employ a guard, *m*, which consists of a plate pivoted at *n* and slotted so as to fit over the roller *j*. The bags pass under this guard, and as soon as the plate *l* moves away from the roller *j* the guard *m* falls by its own weight, assisted by a spring, *o*, if desirable, and carries the bag directly away from the paste-roller.

Attached to the box *H* on the side opposite the blade or scraper *k* is a creasing blade or knife, *p*, which may be adjusted downward by screws *p*', and in the yokes *l* just forward of the plate *l* is mounted a creasing-roller, *p*², composed of india-rubber or other elastic material which is soft, and into which the blade or knife *p* may indent itself. When the yokes *l* and the supporting-plate *l* are moved up, so also is the creasing-roller *p*² moved up against the blade or knife *p*, and thereby is the bag creased at the juncture of the flap *a*⁴ with the bag, so that the said flap will stand up at an angle of about forty-five degrees to the bag. The sudden movement of the plate *l* away from the paste-roller *j* prevents the paste from being applied to too large a portion of the bag, and the roller *L* is of such small diameter that ample space is left between it and the paste-roller *j* for the passage of the bag forward while the paste-box moves backward without any danger of pasting the bag beyond its extreme lower or bottom portions.

In order to bring the paste-roller *j* over the supporting-plate *l* at precisely the right time, I preferably make the connecting-rod *J* adjustable in length, and this may be done by making them in two pieces connected by a screw-threaded sleeve and jam-nuts, as clearly seen in Fig. 14. After the bag is released from between the paste-roller *j* and the plate *l* and has been creased, it is still held between the small roller *h*' and the traveling endless belt *F*, and said roller and belt do not release their hold upon the bag until it enters between the pressing-rollers *O O'*, the former of which may be rotated positively by any suitable gearing from some other shaft of the machine, and the latter of which rotates by frictional contact with the bags. These pressing-rollers *O O'* press the flap *a*⁴ down upon the pasted portion of the bag and complete all the operations of making the bag, and before the bag leaves the rollers *O O'* it enters between two rollers, *P P'*, which again press it and aid in smoothing and finishing the bags. The lower roller, *P*, is rotat-

ed positively, while the upper roller, *P'*, rotates by frictional contact with the bag.

From the final pressing-rollers *P P'* the bags are delivered into a box or other suitable receptacle and are tied together in bundles, after which they only require to be dried to prepare them for sale.

What I claim as my invention, and desire to secure by Letters Patent, is—

1. A knife for a paper-bag machine, composed of a straight stock-piece, a bowed stock-piece detachably secured thereto, and a sectional blade, substantially as herein specified.

2. A knife for a paper-bag machine, composed of a straight stock-piece cut away upon the under side, a bowed stock-piece slotted at each end to form two fingers, the upper of which are detachably secured to the straight stock-piece, and the lower of which lap under the same, and the sectional blade, substantially as herein specified.

3. The combination, with the roller *D'* and the reciprocating knife carried thereby, and composed of the main stock-piece *e* and blade-sections *f*, and the removable stock-piece *e'* and blade-section *f'*, of the roller *D*, having a slot composed of the narrow end portions, *g*, and the wider intermediate portion, *g'*, substantially as herein specified.

4. In a paper-bag machine, the combination of two rollers, between which the paper passes, having circumferential beads and corresponding grooves near each end, and having the portions on the outer sides of and between said beads and grooves of cylindric form and uniform diameter, and a reciprocating knife carried in one of said rollers, substantially as herein specified.

5. In a paper-bag machine, the combination of a paste-box, a reciprocating carriage supporting said box, and guides therefor, and a crank-shaft and a connecting rod or rods for operating said carriage, substantially as herein specified.

6. In a paper-bag machine, the combination of a paste-box, a plate for supporting bags while paste is being applied, a shaft with which said plate rotates, and mechanism, substantially as described, for moving said plate toward and from the center of the shaft, substantially as herein specified.

7. In a paper-bag machine, the combination of a creasing blade or knife, an elastic creasing-roller, a shaft with which said roller rotates, and mechanism, substantially as described, for moving said roller toward and from said shaft, substantially as herein specified.

8. In a paper-bag machine, the combination of a paste-box, a creasing knife or blade, a plate for supporting the bags while paste is being applied, an elastic creasing-roller, a shaft with which said plate and creasing-roller rotate, and mechanism, substantially as described, for moving said plate and roller toward and from said shaft, substantially as herein specified.

9. In a paper-bag machine, the combination of a reciprocating paste-box, a plate for supporting bags while paste is being applied, a shaft with which said plate rotates, yokes to which said plate is attached, and cams for moving said yokes and plate from the center of said shaft, substantially as herein specified.
- 5 10. The combination of the paste-box H, the creasing blade or knife p, the plate p^2 , the sliding yokes l^1 , the elastic creasing-roller p^2 , and to the cams N, substantially as herein specified.

EDWARD STANLEY.
